(57) **CLAIM**

The ornamental design for a cradle cover for a vehicle entertainment system, as shown and described.

DESCRIPTION

FIG. 1 is a front perspective view of a cradle cover for a vehicle entertainment system showing my new design.

FIG. 2 is a rear perspective view of thereof.

FIG. 3 is a front plan view of thereof.

FIG. 4 is a rear plan view of thereof.

FIG. 5 is a bottom view of thereof; and,

FIG. 6 is a side view of thereof.

The broken lines in the drawings are for the purpose of showing environmental structure and do not form part of the design to be patented.
